UNITED STATES PATENT OFFICE.

HENRY WYNKOOP, OF PHILADELPHIA, PENNSYLVANIA.

DESIGN FOR GIMP.

SPECIFICATION forming part of Design No. 16,076, dated May 5, 1885.

Application filed March 18, 1885. Term of patent 7 years.

To all whom it may concern:

Be it known that I, HENRY WYNKOOP, a citizen of the United States, residing in the city and county of Philadelphia, State of Pennsylvania, have invented and produced a new and original Design for Gimp, of which the following is a specification, reference being had to the accompanying photographic illustration, forming part thereof.

10 The leading feature of my design is the representation of a series of keystones.

A represents a piece of gimp having on its face an ornamental figure which is formed of a cross-bar, *a*, and side bars, *b*, connected therewith, the said bars *a* extending from the outer ones of the side bars, and the said side bars

extending diagonally toward each other, producing a series of keystones throughout the length of said piece.

I claim—

20 The design for gimp herein shown and described, the same consisting of a heading provided with transverse bars *a* and side bars, *b*, the said transverse bars *a* extending to the outer ones of the said bars *b*, and the said side bars being successively by pairs nearer together, forming a keystone, substantially as described.

25 HENRY WYNKOOP.
